UNITED STATES PATENT OFFICE

WILLIAM WELTON EDWARDS, OF LOS ANGELES, CALIFORNIA

DRILL PRESS FEED

Application filed November 12, 1928. Serial No. 318,650.

My invention relates to a drilling machine of the type commonly known as radial drills, in which a drill is carried in a chuck adapted to rotate on a vertical axis, which chuck is 5 mounted so that it may be swung horizontally in an arc to various positions around a standard and disposed at various positions radially of the pivotal center of the standard, and also be disposed at various levels.

10 An object of my invention is to provide a mounting in a drilling machine of the above character which is so constructed as to permit ready adjustment of the drill to various positions both horizontally and vertically, 15 and by which the drill may be maintained in its adjusted position.

Another object is to provide a means whereby a drill carried on an adjustable support of the character described may be driven continuously and be manually fed to or withdrawn from the work either by means of a screw feed as in effecting slow advance or retracting of the drill relative to the work, or by a lever-controlled feed in effecting rapid 25 advance or retraction of the drill relative to the work.

A further object is to provide a machine of the above character in which the parts are of simple construction and adapted to 30 be readily assembled or dismantled, and in which the wearing parts may be readily lubricated and be easily removed and replaced in event of excessive wear.

With the foregoing objects in view together with such other objects as may subsequently appear, my invention resides in the parts and in the construction, combination and arrangement of parts hereinafter described and claimed and illustrated in the accompanying drawings, in which:

Fig. 1 is a fragmentary perspective view showing my device in full assembly on the radial bracket of any ordinary radial drill assembly.

Fig. 2 is a fragmentary view showing the ball thrust bearing for holding the drill shaft;

Fig. 3 is a view taken on line 3—3 of Fig. 4;

Fig. 4 is a section taken on line 4—4 of Fig. 1;

Fig. 5 is a section taken on line 5—5 of Fig. 4;

Fig. 6 is a section taken on line 6—6 of Fig. 4.

Referring to the drawings more specifically and particularly to Fig. 1, where a general assembly of my device is shown, 45 indicates a guideway pivotally mounted upon any supporting column (not shown), the outer end of said guideway being supported by a diagonal strut 46, which strut is suitably connected to the column (not shown). Extending parallel with the guide 45 and on one side thereof there is provided a revolute shaft 48 which is supported at the outer end by bearing 50 and on the other end by a suitable bearing on the column support (not shown).

Mounted upon the guideway 45 is a carriage designated in its entirety by numeral 20.

The carriage embodies a back wall portion 60 mounted to slide on the guideway 45, there being a dove-tail sliding engagement between the upper and lower edges of the guideway 45 and the back wall 60 of the carriage, as indicated at 61 and 62 in Fig. 4, and projecting upwardly from the back wall 60, are vertical parallel members 63 and 64, having front faces *a* and *b* extending flush with the front face *c* of the back member 60. Mounted on the front of the back wall portion 60, is a 80 housing embodying a pair of side walls 65 and 66 having inner end faces *d* and *e* which abut against the face *c* of the back wall. The side walls 65 and 66 terminate on a corresponding horizontal plane above the back 85 wall 60 as indicated at *f* in Fig. 3, there being projections 67 and 68 however extending from the inner upper edges of the side walls 65 and 66 lying over the upper portion of the members 63 and 64 on the back wall.

The members 67 and 68 are secured to the members 63 and 64 by screws 69 or by suitable fastenings. The side wall portions 65 and 66 are connected together adjacent their lower ends by a transverse wall 70 which 95 abuts against the wall *c* on the back wall member 60, the upper and lower edges of the wall portion 70 extending flush with the upper and lower edges of the back wall 60, as particularly shown in Fig. 4. The adjacent 100

faces of the walls 60 and 70 are formed to receive a bearing 71 through which a vertical revoluble shaft 72 extends, as will be later described. The upper portion of the side walls 5 65 and 66 project beyond the lower portions thereof, and extending over the space between the upper portions of the side walls 65 and 66 is a cover plate 73 which comprises a vertical wall 74 which abuts against the outer vertical 10 edges of the side walls 65 and 66 and also embodies a horizontal wall 75 which seats on the upper edges of the side walls 65 and 66, as particularly shown in Figs. 3 and 4. The lower portions of the side walls 65 and 66 extend adjacent the horizontal revoluble shaft 48 and are formed to receive a bearing 76 through which the shaft 48 extends.

The front face of the back member 60 is formed with spaced channels 97 and 98 which 20 extend upwardly throughout the lengths of the portions 63 and 64, as distinctly shown in Fig. 6, and the inner faces *d* and *e* of the walls 65 and 66 of the outer portion of the carriage are formed with vertical channels 25 99 and 100, as particularly shown in Fig. 6, which are designed to align with the channels 97 and 98 when the front and back members are fastened together to form vertical 30 guideways in which are slidably mounted 35 rack bars 101 and 102, as particularly shown in Fig. 6. The upper ends of the rack bars are connected to a cross head 103 in which the upper end of the vertical shaft 72 is journaled; the shaft 72 being formed with a reduced upper end portion 104 which passes 40 through the cross head 103 and is fitted with a collar 105 which bears on the cross head and supports the shaft 72.

An end thrust bearing is interposed between 45 a shoulder 107 and the under side of the cross head 103, as distinctly shown in Fig. 2. Arranged within the front portion of the carriage are idler spur gears 108 and 109 mounted on a shaft 110 journaled in the walls 65 and 66, as shown in Fig. 6, which 50 spur gears mesh with the rack bars 101 and 102 and also mesh with spur gears 111 and 112 fixed on a shaft 113 journaled in the walls 65 and 66. The shaft 113 projects 55 through the wall 66, and affixed to its end is a disk 114 formed with peripheral sockets 115 adapted to receive a demountable lever, not shown, by means of which the disk 114 may be manually rotated to revolve the 60 shaft 113 and effect longitudinal movement of the rack bars 101 and 102 to move the shaft 72 longitudinally relative to the carriage to advance or retract a drill 116 carried in a chuck 117 on the shaft 72 relative to the work which may be supported on the base (not shown). By this means, rapid vertical 65 movement of the drill may be effected.

As a means for retracting or advancing the 68 drill by a screw feed, the shaft 113 is fitted with a worm wheel 118 with which a worm

119 may be engaged; the worm being mounted on a shaft 120, the inner end of which is supported on a horizontally pivoted bearing 121, the outer end portion of which is journaled in a bearing 122 adapted to be shifted vertically whereby the worm 119 may be thrown into and out of engagement with the worm wheel 118. The outer end of the shaft 113 is fitted with a hand wheel 123 by means of which the shaft and worm may be manually rotated. The bearings 121 and 122 are carried by the carriage member 73; the bearing 121 being pivoted in a depending wall 124 formed on the top wall 75 of the latter, and the bearing 122 being carried in a vertically elongated slot 125 formed in the front wall 74. A spring 126 mounted in a recess 127 in the wall 74 exerts an upward pressure on the bearing 122 to normally position the shaft 120 at an incline with the worm 119 out of mesh with the worm wheel 118, the worm 119 being maintained out of mesh when the shaft 113 is to be rotated through the disk 114.

Depending from the shaft 120 in front of the plate 74, is an arm 128 having a shoulder 129 adapted to be engaged with a pin 130 on the plate 74 when it is desired to hold the shaft 120 in position to mesh the worm 119 with the worm wheel 118. When the work is thus meshed with the worm wheel, the drill 116 may be advanced or retracted relative to the work by a screw feed. By mounting the worm shaft 120 on the cover member 73, it may be readily placed in operative relation to the worm wheel in assembling the machine.

As a means for counterbalancing the rack bars and the drills carried thereby, the cross head 103 is connected to a cable 131 wound on a spring reel 132 which acts to exert a yieldable upward pull on the cross head.

The carriage member 20 is normally free to slide on the guide 45 and is fitted with a handle 133 by which it may be manually grasped and advanced or retracted on the guide 45.

The operation of the invention is apparent from the foregoing, it being seen that by turning on the column (not shown) the drill may be moved to various positions on an arc concentric with the axis of the column, and by shifting the carriage on the guide, the drill may be disposed at various positions radially on the axis of the column.

And by operating either the disk 114 or hand wheel 123, as before described, the drill 120 may be fed to the work or retracted therefrom either by lever or screw action.

While I have shown and described the specific embodiment of my invention, I do not limit myself to the exact details of construction and arrangement shown, but may employ such modifications and changes as come within the scope of the appended claim.

I claim:

In a drill press feed, a carriage, a pair of

rack bars slidable vertically on said carriage, a drill-supporting shaft carried by said rack bars, a housing on said carriage having side walls, a shaft journalled in said side walls
5 and extending therebetween, gear connections between said shaft and said rack bars, a worm wheel fixed on said shaft between said side walls, a top plate, a depending face plate on said top plate formed with a slot, said top
10 and face plates being demountably carried on said side walls, a pivoted bearing carried by said top plate, a shaft journalled in said bearing projecting through the slot in said face plate, a worm carried on said last
15 named shaft adapted to mesh with said worm wheel, a spring carried on said face plate acting on said worm carrying shaft to normally maintain the worm out of engagement with said worm wheel, an arm on said
20 worm carrying shaft, means on said face plate engageable with said arm to hold said worm in engagement with said worm wheel in opposition to said spring, and hand operated means for rotating said worm carrying shaft.
25 In testimony whereof, I have affixed my signature.

WILLIAM WELTON EDWARDS.
